SOFA OR SIMILAR ARTICLE

William H. Oliver, 1219 N. 50th, Seattle, Wash. 98103

Filed Mar. 15, 1971, Ser. No. 124,614

Term of patent 14 years

Int. Cl. D6—02

U.S. Cl. D6—61

FIG. 1 is a perspective view of a sofa showing my design.

FIG. 2 is a top view of the sofa.

FIG. 3 is a front elevation view; and

FIG. 4 is a left elevation view.

The rear elevational view of the sofa resembles a front elevational view of the backrest of the same.

I claim:

The ornamental design for a sofa or similar article, as shown and described.
